UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

SHOE-MACHINE.

1,113,085.

Specification of Letters Patent.

Patented Oct. 6, 1914.

Application filed August 21, 1910. Serial No. 579,864.

To all whom it may concern:

Be it known that I, ORRELL ASHTON, a citizen of the United States, residing at Swampscott, in the county of Essex and State of Massachusetts, have invented certain improvements in Shoe-Machines, of which the following description, in connection with the accompanying drawings, is a specification, like reference characters on the drawings indicating like parts in the several figures.

This invention relates to pulling-over and other machines for use in the manufacture of boots and shoes and has for its object to improve the mechanism by which a shoe is supported in such machines.

In the pulling-over machine in which the invention is shown as embodied for the purpose of explanation, said machine being illustrated and fully described in United States Letters Patent No. 663,777 granted December 11, 1900, the shoe, containing a last, is positioned with its sole faced upwardly against a bottom rest. It was found in practice that the action of the upper pulling devices of the machine tends to displace the last rearwardly in the machine during the pulling-over operation and the machine was equipped with a heel rest as explained in United States Letters Patent No. 1,029,387, granted June 11, 1912, on an application filed March 28, 1903. In the further development of the machine for work not originally required of it, particularly in strongly pulling the upper lengthwise of the last and up over the toe, a tendency has appeared for the last to fulcrum on the sole rest, allowing the heel end of the last to descend more or less and the toe end of the last to fail to resist the pull of the grippers. It is objectionable to employ in a pulling-over machine the known means, such as heel spindles, for holding up the heel end of the last because of the additional time which would be required to spindle the last and adjust it, and for other reasons.

In view of these considerations an important feature of this invention consists in an external heel end rest for a shoe having provision for supporting the heel end of a shoe containing a last in inverted position against downward displacement of the last. The upward pull on the upper holds the shoe

against the feet of the bottom rest securely enough to prevent bodily forward movement of the last.

In the preferred embodiment of this invention herein shown for exemplification I have taken advantage of this fact by forming the heel rest to prevent downward movement of the heel end of the last without an accompanying forward bodily movement of the last. In the embodiment shown the oppositely inclined heel end embracing faces of the heel rest have last supporting portions which are inclined forwardly at a sharp enough angle to extend under the last or shoe and prevent downward displacement in the direction of movement about the sole rest as a fulcrum.

Another feature of the invention consists in providing an external heel end rest with a last sustaining member which is adjustable in the direction of the height of the last. This has the advantage of affording provision for sustaining against depression lasts of widely differing thickness with their soles in substantially the same plane. Herein the heel rest comprises a back plate upon which is carried members provided with heel engaging faces which are inclined forwardly at an acute angle to the plane of the sole rest and which are adjustable together perpendicularly to that plane.

These and other features of the invention will now be described in connection with a preferred embodiment of this invention and will then be pointed out in the claims.

Figure 1 is a side elevation of a pulling-over machine embodying this invention; Fig. 2 is a perspective of the new heel support; Fig. 3 is a section on line 3—3 of Fig. 1.

The pulling-over machine is made substantially like that described in the Patent No. 663,777 before mentioned. This machine comprises grippers which seize the upper at the sides of the forepart and at the toe of the shoe and pull it upwardly to stretch it about a last that is presented in inverted position against a sole rest 2. The shoe is held by means of an external heel end rest against rearward displacement which might be effected. This rest is sustained by parallel arms 4 which are free to swing laterally to position the heel rest

transversely of the machine and also have a limited swinging movement backwardly against the locking bar 5 for securing the rest in transversely adjusted position. These features of construction are more fully described in the specification of the Patent No. 1,029,387, before mentioned and their exact arrangement forms no part of the present invention.

- 10 The forwardly extended portions of the arms 4 are connected to a back plate 10 which in the present example is V-shaped, the wings thereof being inclined forwardly and outwardly at similar angles to the median plane of the machine. The heel engaging member 12 of the heel rest is also of similar V-shape in its general outline and is mounted on the back plate for vertical adjustment. The illustrated provision for 15 this adjustment comprises gibs or clamping locks 14 having lips on their rear sides between which and the engaging member 12 the edges of the back plate are clamped by screws 15. This mounting permits any 20 desired relative vertical adjustment of the members 10, 12. The upper portions of the wings of the member 12 are beveled as at 20 to provide faces adapted to extend under the rear end face of the inverted last and 25 support the heel end of the last against downward displacement. The tendency to such displacement results from the severe pulling by the toe gripper upwardly against the toe end of the last which tends 30 to cause the last to fulcrum upon the sole rest 2 and swing the heel end downwardly. The inclination of the faces 20 to the plane of the last bottom or the plane of the sole rest is such that the last is prevented from 35 swinging downwardly about the sole rest as a fulcrum. In order that the last might swing downwardly about said fulcrum the shoe would have to be displaced forwardly, requiring it to slide along the inclines 20. 40 Such forward displacement of the shoe is prevented by the frictional engagement of the usual toothed faces of the sole rest with the shoe bottom. It will be noted that the seat formed by the faces 20 is adapted to 45 embrace the cone portion of the rear end of the last, said faces being for this purpose downwardly inclined both inwardly and forwardly to provide sustaining means extending under the last.
- 50 The member 12 is provided at the intersection of its diverging faces with a vertical groove 22 to receive the usual tack which is partially driven into the heel end face of the shoe during the assembling operation.
- 55 The provision of this groove avoids engagement of this tack with the shoe engaging faces and thus prevents the injury to the heel rest and such injury to the shoe as might result if the tack were bent over upon 60 and jammed into the upper.
- 65

In the use of the invention the member 12 will be adjusted in accordance with the class of work to be done, whether men's, women's, or children's shoes, into a vertical position where it will embrace the cone of the last and where the diverging sides of the last, as the last becomes fuller toward the sole plate, will rest upon and be sustained by the faces 20. The machine will then be used as described in said prior patents.

Having explained the nature of this invention and described a preferred construction embodying the same I desire to secure by Letters Patent of the United States protection for all of the patentable features and combinations herein disclosed and the following claims are to be interpreted and construed broadly in the light of this intention.

I claim—

1. In a machine of the class described an external V-shaped heel end abutment or rest having forwardly inclined, angularly related faces for supporting the heel end of an inverted shoe against downward displacement. 85
2. In a machine of the class described an external heel rest having diverging heel end embracing faces, portions 20 of which are formed to extend forwardly and downwardly at an angle to compel bodily forward movement of a last when the latter descends relatively to said rest and in co-operative relation therewith. 90
3. In a machine of the class described, an external heel rest having diverging heel embracing faces, portions of which are obliquely inclined forwardly to compel bodily forward movement of a last when the latter descends relatively to said rest and in co-operative relation therewith. 100
4. In a machine of the class described an external heel rest having rigid diverging faces to embrace the sides of the heel of a shoe containing a last and sustaining portions inclined to the plane of the shoe bottom to prevent downward displacement of the heel end of the last from normal position except when accompanied by forward movement of the last. 105
5. In a machine of the class described an external heel rest, and a sole rest arranged to engage the forepart of a shoe containing a last, said heel rest having shoe supporting faces inclined forwardly into position to prevent downward movement of the heel end of the last about the sole rest as a fulcrum. 110
6. In a machine of the class described an external heel rest having forwardly inclined sides to embrace the heel end of a shoe containing a last, and heel end engaging faces which are inclined downwardly and forwardly at an acute angle to the plane of the last bottom for the purpose stated. 125

7. In a machine of the class described an external rest for the heel portion of a shoe comprising a back plate and members adjustable thereon perpendicularly to the plane of the bottom of a shoe which is in co-operative relation with the rest and having oppositely inclined heel embracing faces.
8. In a machine of the class described an external rest for the heel portion of a shoe and shoe engaging means adjustable thereon perpendicularly to the plane of the bottom of a shoe which is in co-operative relation with the rest and having a shoe sustaining face inclined forwardly at an oblique angle 10 to the shoe bottom.
9. In a machine of the class described an external rest for the heel portion of a shoe comprising a V shaped shoe engaging member having heel sustaining faces inclined forwardly at an oblique angle to the plane of the bottom of a shoe which is in co-operative relation with the rest.
10. In a machine of the class described an external heel end rest comprising a back plate, and a shoe engaging member having diverging shoe engaging wings and provided with gibs forming at its lateral edges inwardly facing grooves to receive and adjustably clamp the edges of the back plate.
11. In a machine of the class described an external heel end rest comprising a back plate and a shoe engaging member having a face to extend under the last for sustaining the shoe, and being adjustable to different 15 elevations.
12. In a machine of the class described an external heel end rest having laterally diverging wings, portions of which are beveled toward each other to form shoe end sustaining faces that converge laterally and forwardly.
13. In a machine of the class described a rigid heel end rest having upwardly beveled portions forming a seat comprising forwardly diverging walls to embrace closely the end and side faces of the cone of a last for sustaining the last against downward 20 and also rearward displacement.
14. In a machine of the class described a rigid heel end rest having a seat comprising upwardly beveled forwardly diverging walls to embrace closely the end and side faces of the cone of a last, said upwardly diverging 25 walls being extended below the last for the purpose described.
15. In a machine of the class described a V shaped rest for the heel portion of a shoe, the wings of which have upwardly and outwardly flaring last end supporting faces which are inclined at an oblique angle to the plane of the shoe bottom.
16. In a machine of the class described a V shaped heel rest, the wings of which support for vertical adjustment thereon shoe engaging members which have upwardly 30 and outwardly flaring last end sustaining faces.
17. In a machine of the class described, shoe positioning means including an external heel end rest for the shoe formed with portions which extend forwardly and downwardly at an oblique angle to prevent downward movement of the heel except when accompanied by forward movement, and other means to prevent such forward movement.
18. In a machine of the class described shoe positioning means including a sole rest constructed and arranged to prevent longitudinal movement of the shoe containing a last when the shoe is pressed into co-operative 35 relation with said rest, and an external heel end rest formed with a shoe engaging portion that is inclined downwardly and forwardly at an acute angle to the plane of the sole rest to provide sustaining means 40 extending under the shoe for preventing pivotal movement of the last relatively to the sole rest as a fulcrum.
19. In a machine of the class described an external heel end rest formed and arranged to embrace an inverted shoe near the cone of the last and to support the shoe from downward displacement by the engagement of the upper portion of the rest with the sides of the shoe opposite those portions of the last which flare or broaden from the cone of the last toward the sole face of the last.

In testimony whereof I have signed my name to this specification in the presence of two subscribing witnesses.

ORRELL ASHTON.
